UNITED STATES PATENT OFFICE.

WILLIAM HENRY STREEPER, OF PHILADELPHIA, PENNSYLVANIA, ASSIGNOR TO
STOKES & SMITH COMPANY, OF SUMMERDALE, PHILADELPHIA, PENNSYLVANIA, A CORPORATION OF PENNSYLVANIA.

MANUFACTURE OF CONTAINER STRUCTURES.

1,297,748.

Specification of Letters Patent. Patented Mar. 18, 1919.

Application filed April 12, 1918. Serial No. 228,080.

To all whom it may concern:

Be it known that I, WILLIAM HENRY STREEPER, a citizen of the United States, residing at Philadelphia, in the county of Philadelphia and State of Pennsylvania, have invented new and useful Improvements in Manufacture of Container Structures, of which the following is a specification.

This invention relates to the manufacture of container structures produced from a single blank, the invention pertaining more particularly to apparatus adapted to produce structures of this general type.

While containers have heretofore been produced from one-piece blanks, such containers are generally so formed as to require the addition of an outer wrapper—generally applied after the container has been filled and closed—this wrapper being designed to provide the finished appearance to the package. Other form of container structures—such for instance as shells—have also been provided, but these have generally been of a composite formation, such for instance as by the use of a scored blank of heavy paper-board, this being folded into the desired shape, after which a thin paper wrapper is applied to the exterior faces thereof and generally inturned on to the inner side of the shaped blank.

On the contrary, the present invention is designed to provide the complete structure formation—whether in the form of a container or of a shell—from the single blank, and the invention contemplates the use of a blank of comparatively light stock and weight and which may have characteristics of pliability, although the invention is not limited in these respects.

Obviously, the commercial success of container structures of this type is dependent to a more or less extent upon the ability to manufacture in quantity, the relative cost of manufacture, and the character of the finished product as to appearance and serviceability.

While the present invention relates to the apparatus for manufacturing container structures of this general type and not to the product, the ability to provide the satisfactory product is an essential in the apparatus. And in order to produce this result,

certain problems must be solved in order that the desired result can be obtained, and to permit understanding of these problems, a short statement is made as to the container structure itself.

A container structure must necessarily have the stiffness requisite for service in the particular use to which it is to be put, and this stiffness is obtainable in various ways. For instance, in the type of container above referred to, this is obtainable by special and more or less complicated forms of blanks, but the resultant container is generally of such appearance as to require the use of an additional wrapper in order to produce the desired finished appearance. On the other hand, shell structures are dependent mainly upon the stiffness of the material employed in the heavy stock blank. When, however, the container structure is formed complete from a single blank which, for instance, may carry the printed matter preliminary to the container-forming operation, the particular formation becomes of material importance in order that the proper container appearance may be had. And when the blank is formed from a more or less pliable stock, the problems are further complicated by the necessity for producing the desired stiffness by means other than the stiffness of the material itself.

Container structures capable of meeting these conditions are known to me, and are illustrated in the accompanying drawings, these structures being in both container and shell form, and are of two general types, each, however, being designed to provide the complete structure from a single blank and to provide such structure where the blank is of pliable material. In these structures, the desired stiffness is provided by the manner of folding and the manner in which the folded parts are secured together and reinforced. For instance, in one of the types, the container has the end formation as a unitary structure and foldable into a multi-ply end formation, the arrangement being such as to have predetermined folding lines in the formation, the multi-ply structure being held in its folded position by means of a marginal end lap which extends from the outer face of the formation over the exposed edges of the

plies and on to the inner face of the formation, the adhesive securing of the end lap in position retaining the end formation against opening and providing the desired 5 stiffness to that formation. To give the stiffness to the front wall (if the container formation is produced) or to the front and rear walls (if the shell formation is produced), the edges of such walls are reinforced by 10 the infolding of a marginal lap carried by the walls, the result being that in the finished container, the three walls have edges which are reinforced by a marginal lap structure, while in the shell formation all of the walls 15 have edges which are so reinforced.

In the other type of container structure, the end formation is provided by wings which are turned in, one of the wings forming the outer face of the end formation and carrying the marginal end lap as in the other type, the principal difference being that this second type requires additional adhesive connection in securing the wings together, the end lap structure being applied 25 as in the first type.

From this statement of the general types of the container structures, it will be readily understood that a number of problems are presented which are not met with in the container structure formations heretofore manufactured by machines. For instance, the absence of material stiffness in the stock of the blank provides a problem in that a substitute for this stiffness must be provided 30 in order that proper folding action can be obtained; while this substitute can be provided by the use of a form, the problem relative to the latter is complicated by the necessity for inturning the adhesively coated laps on to the inner face of the folded blank while the latter is being held. Another factor is the necessity of operating in 35 connection with an adhesively coated blank; while adhesively coated blanks have heretofore been employed for wrapping packages or covering machines, these blanks have 40 been of thin paper stock.

Another problem, in this connection, and which will be understood from the difference 45 in the types of containers shown, is the question of apparatus for producing these container structures, it being readily understood that where special machines are required for producing a particular type, the cost of manufacture of the container structure is necessarily increased, even though such machines might be designed to take care of the condition of variation in 55 sizes of the structure.

60 Among the general objects of the invention, therefore, are to be found:

(a) The provision of apparatus adapted to produce complete container structures from a single blank;

65 (b) The provision of apparatus capable

of producing container structures of different types;

(c) The provision of mechanism for producing these results in connection with standard machines adapted for other purposes to make possible the production of container structures of this general type by simple changes in standard machines so as to reduce the cost of apparatus for this particular purpose to a minimum.

To these and other ends, therefore, the nature of which will be readily understood as the invention is hereinafter disclosed, said invention consists in the improved construction and combination of parts herein- 75 after more fully described, illustrated in the accompanying drawings, and more particularly pointed out in the appended claims.

In the accompanying drawings, in which similar reference characters indicate similar 80 parts in each of the views:

Figure 1 is a fragmentary view in side elevation showing a portion of a standard or organized machine modified to carry out the present invention.

Fig. 2 is a top plan view of the blank-receiving table.

Fig. 3 is a top plan view of portions of the folding mechanisms located below the blank-receiving table, the latter being omitted.

Fig. 4 is a perspective view, more or less diagrammatic, showing the initial stage of the folding operation.

Fig. 5 is a perspective view, with parts broken away, showing portions of the folding mechanism, the view indicating a succeeding stage of the folding operation.

Figs. 6, 7 and 8 show respectively succeeding stages of the folding operation, Figs. 6 and 7 being views partly in front elevation and partly in section, Fig. 8 being a view in transverse section.

Fig. 9 is a perspective view, with parts broken away, of one form of container structure.

Fig. 10 is a perspective view showing the blank from which the container of Fig. 9 is formed.

Figs. 11, 12, 13 and 14 are perspective views indicating different stages of the folding operation when the blank of Fig. 10 is employed.

Fig. 15 is a perspective view showing a blank adapted for the production of a shell.

Fig. 16 is a perspective view of a shell 120 made from the blank of Fig. 15.

Fig. 17 is a view similar to Fig. 15 showing a blank of a different type.

Fig. 18 is a detail perspective view illustrating a change made in operation by reason of the use of the blank of Fig. 17, the view corresponding to the stage illustrated in Fig. 5.

Before describing the apparatus for producing the container structures, I will first 130

give a brief description of various forms of container structures which are capable of being produced, in order that the solution to the different problems of apparatus requirements will be more clearly understood.

One general form of container structure is shown in Figs. 9 and 14, this structure being formed from a blank of the general character indicated in Fig. 10, wherein *b*

10 indicates the bottom section, *a* and *c* the front and rear wall sections respectively, and *d* a closure section, each of sections *a*, *b* and *c* carrying wings *a'*, *b'*, and *c'*, these wings, in this particular form, being integrally connected together, the combined length of the wings equaling the length of the corresponding sections of the blank. Wing portion *b'* additionally carries a marginal end lap *b*² which is adhesively coated, 15 and wing portions *a'* and *c'* are preferably arranged with a weakened line formation indicated at *x*. In addition, section *a* carries a marginal side lap *a*² also adhesively coated, while section *d* carries wings *d'* and 20 an end lap *d*². It will be noted that Fig. 10 shows the outer corner of wing portions *a'* and *c'* as cut away or omitted; this is to facilitate folding, but is not essential.

In producing the container from the 25 blank, sections *a* and *c*, with their wing portions, are first brought into a position perpendicular to the plane of bottom section *b*, section *d* extending in the plane of section *c*, thus producing a more or less trough-like structure such as shown for instance in Fig. 30 11 (also Fig. 4). Wing portions *a'* and *c'* are then folded inwardly, each producing a two-ply structure, one of the wing portions being folded slightly in advance of the other 35 in order that the two structures may be properly folded to produce a multi-ply end formation, an intermediate stage of the folding operation being shown in Fig. 12 (also in Fig. 5). This infolding of wing portions

40 *a'* and *c'* also has the effect of raising wing portion *b'*, the completion of the folding of wing portions *a'* and *c'* practically bringing wing portion *b'* into position perpendicular to the plane of section *b*; thus 45 producing a multi-ply end formation of which wing portion *b'* forms the outer ply, the two-ply formations of each of wings *a'* and *c'* being in more or less of a superposed relation with the inner ply of one of these 50 wing portions forming the inner ply of the composite end formation, the structure at this stage having the body portion of the container folded, with laps *a*² and *b*²—each adhesively coated—projecting upward above 55 the top plane of such body portion—relatively upstanding with respect to the plane of the bottom section. These laps are then turned in at angles to the plane of the walls from which they project—the formation 60 shown in Fig. 13—after which the inturned

laps are carried downward—infolded—on to the inner faces of the wall formations and adhesively applied thereto as indicated in Figs. 9 and 14. Section *d* and its wings and laps are not designed to be operated upon, 70 since they form the closure, the wings and laps being adapted to extend into the interior of the container after the commodity has been placed in position.

As will be seen, the front and rear walls 75 of the container are of single thickness of stock, and unless provision is made for reinforcing or bracing the upper edges of these walls, the container is subject to collapsing action. In this particular form of container 80 this stiffening action of the rear wall is provided by the line of fold between sections *c* and *d* which, when the container is closed, provides a fold which is of right angular formation, the fold thus acting as a stiffening means similar to the folds between the front and rear walls and the bottom wall. However, the upper edge of the front wall is of the free edge type, and to provide the desired stiffness, the free edge of this wall 85 is stiffened by the reinforcing action of side lap *a*², thus providing a two-ply thickness at this upper edge with the plies adhesively connected.

The end formations are of multi-ply thickness, the particular manner in which the folding is provided serving not only as a brace for the ends, but also producing a strong and substantial formation. This multi-ply formation being folded and simple, must be maintained in folded position, and this is provided by the infolded laps *b*² which join the inner and outer plies of the formation, overlying the edges of the intermediate plies, this arrangement being such 100 as to maintain the end formation intact by the single point of adhesive connection. In addition, these end laps *b*² also serve as reinforcing laps.

As will be readily understood, apparatus 110 for producing a structure of this type must be capable of providing the folding operations in a positive manner, and since the material may be of a pliable character, the apparatus itself must carry the stiffening 115 structure in order that proper folding may be had. This brings into the question the character of the form to be employed for the reason that the form must not only be capable of functioning as such while the 120 blank is being folded, but in addition, must be of such character as to permit of the infolding of laps *a*² and *b*² into position as well as to provide for application of pressure after the lap infolding action has been 125 had in order that the adhesive connection may be properly made and at least partially set. These two requirements are of material importance.

If, instead of the blank of Fig. 10, I 130

employ a blank of the character indicated in Fig. 15, in which section *d* and its laps are omitted, and a side lap *c*²—adhesively coated—be employed, the blank is foldable 5 into a shell formation, as indicated in Fig. 16, lap *c*² being infolded similarly to lap *a*² and forming a reinforce for the rear wall, the end formations being the same with the two types of blanks.

- 10 Another way of producing the shell formation is by the use of a blank such as shown in Fig. 17, in which wings *a'* and *c'* are separate from wings *b'* so as to provide practically a single ply thickness to 15 a wing excepting at different points. Since there is no positive connection between wing *b'* and wings *a'* and *c'*, these wings are adhesively connected by the use of adhesive zones *b*³ formed on wings *b'*. The 20 laps of the blank are similar to those of Fig. 15. Fig. 18 indicates an intermediate step in the folding of this blank, this view showing the manner in which wings *a'* and *c'* are infolded, wings *b'* then being brought 25 up into contact with the infolded wings *a'* and *c'* and the laps then infolded as in the other form.

Obviously, the blank shown in Fig. 10 may have the wing formation of the blank 30 of Fig. 17, and thus produce a container instead of a shell structure.

As will be understood, each of these particular forms of container structures shown provides for similar problems, the main difference being the manner in which wings *a'* and *c'* are infolded and the particular type of blank employed. But the container structure produced in each case is formed 35 from a single blank; and each structure is not materially dependent upon the stiffness of the material from which the blank is made, the stiffness being provided more or less by the particular fold formation and the manner in which the parts are reinforced. In addition, each form presents the 40 problem of taking care of the blank folding operation, working under single blank conditions, as well as the infolding and securing of the laps in position.

50 As presently pointed out, the problems involved are more or less dependent for solution upon the character of the form employed, this solution enabling standard machines to be employed for the purpose of 55 producing container structures of this type. For the purpose of explaining the invention and the solution to the problems, I have selected, for illustrative purposes only, a standard machine in general use, based 60 more or less upon the disclosure of the patent to Reifsnyder & Fath, No. 1,131,792, dated March 16, 1915, this machine being designed for forming sealed wrapped packages, but which can, by a few simple 65 changes, be converted into a machine capable

of carrying out the manufacture of container structures such as herein disclosed.

This ability to employ standard machines for this purpose by a few simple changes is, of course, of positive advantage in that 70 it permits the production of these container structures as an additional function of such standard machine. As pointed out, the changes in structure are small, and in illustrating the present invention I have there- 75 fore confined myself more or less to the portions of the apparatus which are involved in the changed structure, sufficient disclosure of the standard parts being made in order that inspection of the disclosure 80 herein and that of the patent will clearly indicate the changes, the apparatus practically having the same cycle of operations shown in the patent, so that no detailed description of the organized machine as an 85 entirely need be presented herein, such description being contained in said patent. And in order that the parts may be more clearly identified, corresponding parts of the two structures are, as far as possible, 90 correspondingly indicated by reference characters.

21 indicates the table, having an opening 22 in its center through which the various instrumentalities are made active in the 95 folding operations. 23 indicates a vertical standard having an arm or bracket 24 which projects toward the center line of the machine. Said arm or bracket carries an upright plate 25 provided with two vertical 100 guides 26 between which slide 27 is mounted, the lower end of this slide carrying a pusher block or plunger 28—constituting a portion of the composite form presently described in detail. Slide 27 is given a reciprocating movement to move block 28 through opening 22 by means of counterbalanced lever 29 fulcrumed at 30 on an arm 31 projecting from standard 23, the free end of lever 29 being pivoted to a 105 link 32, and being adjustable within the link by means of a thumb screw 33. The link is pivotally connected to the slide by a pin 34. The vibratory movements of lever 29 on its fulcrum through the action 110 of cam groove 43 of rotating drum 42, provide for reciprocating movements of slide 27, thus imparting similar movements to block 28.

The drive mechanism of drum 42 is not 115 disclosed herein, one form of operating mechanism for rotating the drum being shown in said patent.

Slide 27 carries lugs 46, each lug carrying a slidable rod 47, these rods extending upwardly through suitable openings in plate 25 to a point above this plate where they are connected by crosshead 48. The lower ends of rods 47 are connected to a plate 49 which is secured to an upper pusher block 125 130

or plunger 50 which also forms one of the blocks of the composite form, block 50 having an opening for the passage of stem 27^a of slide 27 and also having openings for the 5 passage of guide pins 28^a carried by the lower pusher block or plunger 28.

Slide 27 and crosshead 48 are connected by a resilient or yielding connection, shown in the form of a coil spring 52, this spring normally tending to cause crosshead 48 to travel with slide 27, but permitting the movement of the crosshead to be restrained without affecting the slide movements at predetermined times, such restraint serving to increase the tension of the spring, so that when the restraint is removed, the spring may act as a power device in causing the crosshead and the parts carried thereby to move rapidly to position. 10 The composite form referred to includes a third or intermediate form block indicated at 200, this block being supported by block 50 through the use of rods or bolts 201 which extend through both blocks, these bolts carrying coil springs 202 located between the blocks, the latter having recesses within which these springs may be housed when the opposing faces of the two blocks are brought practically into contact as presently described. 15 Bolts 201 are shown as having a head exposed on the under face of block 200, the opposite end of the bolts carrying nuts which permit of adjustability of the maximum distance between these blocks when the blocks are separated. 20 Where the heads of bolts 201 are exposed in this manner, block 28 may carry recesses 28^b for housing these heads when block 200 is brought into contact with block 28. 25 In practice, the three block members of the form—28, 50 and 200—are normally in contacting position above the blank-receiving plate presently described, the positions of the block members relative to each other being approximately as shown in Fig. 8, 30 block member 28 being positively held by slide 27, while blocks 200 and 50 are held in contact therewith through the action of spring 52 in drawing down crosshead 48, it being understood that the power of spring 52 is in excess of that of springs 202. 35 The composite form is brought into contact with the blank and with the block thus relatively positioned at the beginning of the folding operation, and at a predetermined period in the downward travel of slide 27, crosshead 48 is temporarily restrained from advancing with the slide—the mechanism for this will be presently described—the result being that 40 plate 49 will be held from downward movement, thus temporarily holding block 50 from further downward movement. As block 28 continues its movement, block 200 will follow onward with block 28 under the 45 action of springs 202, until the distance be-

tween blocks 50 and 200 reaches the maximum, whereupon further movement of block 200 will be stopped, continued movement of slide 27 carrying block 28 away from block 200. 70

At the proper time, slide 27 is held from further downward movement, leaving the three blocks in spaced relation, as indicated in Fig. 6, for instance. The succeeding movements of these blocks are provided by 75 releasing the restraint placed on crosshead 48, the result being that blocks 50 and 200 will move downward, retaining the maximum distance therebetween until block 200 again contacts with block 28, whereupon 80 further downward movement of the crosshead will cause block 50 to move downward until all of the blocks are in the position shown in Fig. 8, this downward movement of the crosshead being provided by the action of spring 52. 85

During the downward movement, periods of dwell in movement are had, other than those indicated, for the purpose of providing specific operations which will be presently referred to. These dwells in connection with block 28 are provided by the pattern of groove 43 of drum 42. 90

The means for restraining the movement of crosshead 48 may be provided in any desired form, this action, in the structure of the patent, being in the form of a pivoted lever 60 which has its movement controlled by a cam groove 44 of drum 42, lever 60 carrying a plate or stop 62 which extends into 95 the path of travel of a pin 63 carried by crosshead 48. As will be understood, crosshead 48 is free to move downward with slide 27 as long as pin 63 is out of contact with plate 62, or if, when in contact with such 100 plate, lever 60 is operated at a speed to cause the downward movement of plate 62 to equal the speed of travel of slide 27. If, however, lever 60 is operated to cause plate 62 to restrict free movement of pin 63, crosshead 48 105 will be held from movement, thus increasing the tension of spring 52. Said spring will then operate to bring the several block members into contact as may be permitted by the downward travel of plate 62 or when 110 permitted by the tuck-in devices, it being understood, of course, that spring 52 will normally tend to move plate 49 downward, the contact of block 200 with block 28 and that of block 50 with block 200 limiting the 115 downward movement of crosshead 48 relative to slide 27. 120

Referring now more particularly to the folding and applying mechanisms, 203—203 indicate two plates adjustably supported 125 above opening 22, these plates combinedly forming a support for the blank, and being positioned parallel to each other to form a space therebetween slightly greater than the width of bottom section *b* of the blank, this 130

space extending throughout the length of the blank and being on the center line of the machine. As shown, these plates are adjustable toward and from each other to accommodate for variations in sizes of blanks, and each is adapted to carry any desired form of gage structure 203^a by means of which the blank can be accurately located thereon. If desired, these plates may be mounted to yield upwardly or be otherwise movable from position to avoid possibility of edges of a completed structure contacting with the plates during the return movement of the form which acts to raise the completed container structure from the folding instrumentalities presently described.

The opposed edges of plates 203 coöperate with the form in providing the initial fold to the blank, the form—which has a bottom area substantially equal to the area of bottom section *b*—passing into contact with said section of the blank and carrying the blank downward between these plates into an open-ended throat located below the plates and which may be formed in suitable manner, the drawings indicating the walls of this throat as formed by a plurality of depending plates 204 supported on rods 205. The walls of the throat are preferably arranged to be adjustable relative to each other to accommodate for variations in sizes of blanks, and if desired, the walls may be additionally movable to increase the distance therebetween to prevent difficulty during return movement of the form.

71 indicates the yieldably supported platen of said patent, it being understood that the blank is clamped between platen 71 and block 28 at the beginning of the downward movement of the blank into the throat. Consequently, this initial downward movement of the form—with the blocks in contacting relation—will cause the blank to be folded into an elongated trough-like formation such as indicated in Fig. 4, wings *a'* and *c'* being folded up in a manner similar to walls *a* and *c*, the open ends of the space between plates 203 and the open ends of the throat, permitting wing portions *b'* and laps *b²* to pass downward freely. Where the blank employed is of the type indicated in Fig. 10, section *d* will project upwardly in the plane of section *c*, as indicated in Fig. 4. As will be seen, the contacting positions of the form members locates these members entirely below the plane of laps *a²* (and *c²* in case the blank of Figs. 15 or 17 is employed).

The relative positions of pin 63 and plate 62 are such that slide 27 is permitted a considerable range of movement without disturbance of the relations between crosshead 48 and slide 27, and during this period, the movement of the form is controlled entirely by the pattern of cam groove 43. It is during this period that a dwell is provided in

the downward movement of slide 27, this dwell serving to permit a portion of the folding operation, the character of the fold being determined by the character of the blank. For instance, if the blank of Figs. 10 or 15 be employed, the folding operation during this particular dwell serves to infold wing portions *a'* and *c'* at least to a partial extent, as presently described, and where the blank of Fig. 17 is employed to provide for the inturning of these wing portions of that blank. During this dwell a sufficient amount of inturning action of these wing portions takes place to insure that as the downward travel of slide 27 and the contacting forms is resumed, these wing portions will be in position to permit of the proper folding of wing members *b'*, this latter being provided by rolls or brushes 93—the brush form being preferred—the downward travel of the forms causing the brush to fold wing member *b'* into proper position as the outer ply of the end formation of the container or shell. As in the patent, brush 93 is movable toward and from the operating position. 90

Where the blank has the wing formation of the general type shown in Fig. 17, the infolding of sections *a'* and *c'* may be provided by folders 83 shown in the patent as mounted on bars 81, these folders being of a type which is applicable for use in the folding of a blank of this type. Where, however, a blank of the type shown in Figs. 10 or 15 be employed, I prefer to employ a different type of folder, these being shown 100 more particularly in Figs. 3 and 5.

As shown more particularly in Fig. 5, 206 designates an arm having a slide 206^a adjustably mounted in the direction of length of bar 81, arm 206 carrying a pivot 207 on which is mounted a rocking lever 208. One end of this lever carries a roller 209 adapted to ride in contact with a face of a bar 210 adjustably positioned above bar 81. Lever 208 carries a folding plate or blade 211 of the desired configuration; since each wing member—*a'* or *c'*—is foldable on the line *x* to provide a more or less triangular configuration to the member in folding position, plate or blade 211 is formed to permit of folding in this manner. Roller 209 is maintained in contact with bar 210 by a spring structure 212.

As pointed out in said patent, bar 81 is movable in a direction transverse to the length of the bar and in a substantially horizontal plane, thus advancing toward the positioned blank and then retreating. Since the normal or inactive position of bar 81 is in its position of retreat, arm 206 will 125 be in its rear position, the result being that lever 208 will be held substantially as indicated in the full line position of Fig. 3, due to the fact that bar 210 is not changed in position during the retreating movement 130

of bar 81, bar 210 thus acting in the nature of a cam to swing lever 208, the result being that the folding plates or blades 211 will, at the time of initial downward movement 5 of the blank, be in a position to permit free downward movement of the several wing members. When, however, bar 81 begins its advancing movement, pivot 207 is also advanced, and since bar 210 remains stationary, lever 208 will be permitted to rock on its pivot through the action of spring 212, the result being that plates or blades 211 will not only be moved inward under the inward movement of bar 81, but will, in addition, 10 be swung on pivots 207. As a result, blades or plates 211 are brought into contact with the upstanding wings a' and c' of the blank and, as the advance of bar 81 continues, the continual change in position 15 of the plates or blades will cause these wing members to be each folded inward into a two-ply configuration, the completion of this movement carrying these plates or blades into the position shown in dotted lines in Fig. 3. 20 This position, however, is not reached until after the form has resumed its downward travel, the resumption of movement taking place at an intermediate period of the folding movements of plates or blades 211. This 25 particular arrangement in connection with this blank is found desirable by reason of the fact that the outer ply of each of these wing members is integrally connected with wing member b' , so that to provide for a 30 complete folding of wing members a' and c' , it is more or less essential that wing members b' be also moved to folded position. As this latter is provided by brush or roller 35 93 and the latter is made effective by the 40 downward travel of the form and blank, it will be readily understood that this downward travel is resumed at such time as will cause the coöperative relation of members 93 and plates or blades 211 in completing 45 the fold of the end formation.

As will be readily understood, the parts are so arranged that one of the blades of an end formation is made active slightly in advance of that of the other blade or may 50 be made to travel at a slightly greater speed, in order that the two wing formations are not brought into edge contact, the purpose being to have the wing member of one side follow that of the other side to produce the 55 multi-ply formations, wing member b' being folded to provide the outer ply of this formation.

While the form resumes its downward travel before plates or blades 211 have completed 60 their folding operation, the plates or blades continue effective until the folded positions are reached, it being understood, of course, that the downward movement of the form and the blank simply acts to gradually 65 carry the folded structure below the

plane of these blades, the folds all being below these blades, so that the latter are free to pass out from between the folds. As a result, the blades may remain active in the folding operation until approximately the 70 time when the blank leaves the blades. When this occurs, the function of the blades has been completed, and bars 81 may retreat to place the plates or blades in their inactive positions. As will be understood, the 75 folded relation of wing members a' and c' is retained through the folding of wing member b' by the action of brush 93. And as the latter is located below blades 211, it will be readily understood that by the time 80 wing b' reaches a position where lap b^2 closely approaches the vertical, the relative movements of form and plates or blades will have been such as to insure that the plates or blades will be kept out of contact with 85 the adhesive coating of laps b^2 .

While wings a' and c' of the blank of Fig. 17 may be folded by this particular form of folding mechanism, the latter is not necessary for that type of blank, a simple advance and retreat movement of the folder being sufficient to provide this infolding operation of wings a' and c' , such for instance as is provided by the folders of the patent.

During at least the major portion of this 95 end folding operation, it is desirable that the three members of the form be in their contacting positions in order that a form substantially equivalent to the size of the interior of the container to be formed is 100 present. This enables the desired corner effect to be produced on the various folds and insures a better finished product. However, as heretofore pointed out, it is necessary that laps b^2 be not only inturned, but also 105 infolded so as to contact with and be adhesively secured to the inner face of the container over the top of the latter. Hence it is necessary to provide first an inturning 110 of these laps together with lap a^2 (and lap c^2 if the latter be employed) at approximately right angles to the planes of the walls of which these laps form a part, and then move these inturned laps downwardly 115 within the container. This latter action is provided by the upper form block as in organized machines of this general type for providing the wrapping or covering operations of box shells. However, this latter 120 type of organized apparatus is not entirely satisfactory under conditions of providing for the formation of container structures of the type herein indicated, due to the fact that the upper form block must be separated from the lower block to permit the lap to be 125 inturned and to provide this separation, the upper form block must be moved entirely out of the embryo shell. As a result, the upper edges of the vertical walls of the shell or container would be unsupported against 130

- the inturning pressure which, when a one-piece blank is employed, has the lap to be infolded and the vertical wall as formed of the same material. In the usual shell forming operations, the resistance to the inturning pressure of the light weight covering blank is provided by the stiff material of the second blank. In the one blank type of structures, however, this auxiliary stiffening element of the product is entirely absent, so that a substitute must be found therefor, and this is provided, in the present invention, by the intermediate form block 200.
- At some time after the end folding operations have reached a point where it is safe for block 50 to pass out of the interior of the embryo container or shell, pin 63 passes into contact with plate 62, the result being that block 50 is temporarily held from further downward movement, the continued downward movement of block 28 completing the folding of wings b' , block 200 remaining in contact with block 28—through the action of springs 202—until block 200 reaches the point of its maximum distance from block 50 as determined by bolts 201, whereupon block 200 also becomes stationary, block 28 continuing its movement alone, finally reaching its lower position. The relative adjustments are such that when block 28 has reached its lower extreme of movement, the upper face of block 200 will be approximately flush with the upper edges of folded wings a' and c' , laps b^2 projecting above the top plane of block 200 and opposite the space between blocks 50 and 200. Laps a^2 and c^2 will also be similarly positioned. As a result, the upper edges of the container or shell are physically supported by this block 200 which also has an area corresponding to the area of the bottom of the product, so that when the lap-inturning operations begin on these laps, these wall edges will be absolutely supported against any inward collapsing and the desired pressure can be applied to these laps to produce the bend without affecting the structure.
- The adjustment of bolts 201 and the timing of the movements of slide 27 and crosshead 48 are such that slide 27 will reach its lower extreme of movement when the upper edges of the folded end wings are approximately on the plane of the upper face of presser blocks 98 carried by frame 97, at which time blocks 50 and 200 are separated their maximum distance and block 200 is spaced its maximum distance from block 28, the upper face of block 200 also being approximately on the plane of these wing edges, this being the position shown in Fig. 6. This also locates the front and rear wall sections of the blank in similar position with respect to presser blocks 98 located opposite

these portions of the folded blank. When, therefore, presser blocks 98 are advanced into contact with the opposing faces of the folded blank, the upper portion of the walls of the container or shell are clamped between these presser blocks and form block 200, thus holding each of these walls more or less rigid at this period. 70

The location of the clamped blank in this position places the upstanding marginal laps a^2 and b^2 (and c^2 where the operation is to produce a shell) directly opposite tuck-in fingers 96, these fingers being located at the ends and at the front of the folded blank where the latter is of the type of Fig. 80 10 and additionally at the rear where the blank is of the type shown in Figs. 15 or 17, these fingers being carried by horizontally-sliding frames 95. These tuck-in fingers are normally retracted and are advanced when the folded blank has been clamped in this manner, the result being that these marginal laps are bent inward by the action of these fingers, the latter serving to carry the laps inward to a position where 90 they will lie within the path of movement of block 50 when the latter resumes its downward travel and passes into contact with the laps. 95

As will be understood, the uniformity of fold of these marginal laps is more or less dependent on the start of the fold—the formation of the line of break of the blank—the proper inturning action and formation of the bend being dependent more or less on the start of the bending action. After the line of break has been provided, the inturning movement simply provides the lap movement on this line of break. It is mainly to provide for this initial or starting of the infolding of the laps that the temporary clamping action described is provided, the clamping of the walls insuring the formation of the proper line of break. 100

After this lap inturning action has been 110 started and the line of break formed, this clamping action is not material, and hence the timing cycle is arranged so that at a suitable time after the break has been completed, crosshead 48 is permitted to begin its downward travel under the power of spring 52, this downward movement causing blocks 50 and 200 to move downwardly with the spacing theretwixen maintained by the action of springs 202, this downward movement continuing while fingers 96 are continuing the infolding action, the result being that block 200 is carried downward away from the upper edges of the walls, as for instance shown in Fig. 7, this view showing the 115 parts in a position where block 50 is approaching the point where it becomes active in turning the laps downward, fingers 96 being in their advance positions, block 50 being temporarily arrested by contact with 120 125 130

these fingers (block 200 also being held). The retracting movement of fingers 96 then takes place, releasing block 50, locating the marginal laps properly in the path of travel of block 50.

- 5 As crosshead 48 continues its downward movement, block 200 passes into contact with block 28 and is held from further movement without, however, affecting the operation of 10 the remaining parts carried by crosshead 48, so that block 50 continues its downward movement and enters the space vacated by block 200, the movement of block 50 obviously turning down these laps which have 15 been infolded by fingers 96 and placing these laps parallel to and in contact with the inner faces of the walls of which they form a part, block 50 continuing its movement until it comes into contact with seated block 200, the 20 position shown in Fig. 8, this contact limiting the further downward movement of crosshead 48. After block 50 has reached this position, exterior pressure is applied to the walls of the folded container in order to 25 set the adhesive connection; this pressure application is provided by presser blocks 98.

From the above it will be seen that activity of presser blocks 98 is required at two particular periods, first to provide the 30 clamping action when the line of break is being formed, and during the application of the setting pressure. During the time intervening between these two periods these blocks may be comparatively inactive, and 35 as it is desirable that the downward movement of blocks 50 and 200 be not affected by any pressure conditions, I preferably retract blocks 98 to a desirable extent during this intervening period, thus permitting free 40 movements of blocks 50 and 200. In addition, I prefer to vary the amount of pressure at the two active periods, the initial pressure being a light pressure sufficient only to provide for the temporary clamping action, the 45 second period of activity providing for heavy pressure in order to produce the proper setting action. These conditions are obviously obtainable by the character of the operating cam or cams which controls the 50 operation of these presser blocks. Both pressure applications are made when the form is at its lower extreme of movement.

This setting pressure practically completes the container structure formation, and 55 after these presser blocks have completed their activity, slide 27 is moved upwardly, thus withdrawing the composite form and carrying the container structure from the folding instrumentalities, platen 71 holding 60 the container structure on the form during this form-retreating movement until the platen reaches its upper extreme of movement, at which time the container structure is practically exposed above plates 203 and at a point beyond liability of being stripped

from the form by the apparatus structure. The container is then stripped from the form in any suitable manner, as by hand for instance, and a new blank placed in position.

From the above, it will be readily seen 70 that the successful formation of the container structure is more or less dependent upon the presence of the wall support at the time the line of break is being produced. Since this support can not be provided by 75 the blank itself, it must be provided as a part of the apparatus, and the problem of providing such support as a part of an organized automatic machine is one which must be solved in order to provide for efficient and satisfactory production. As above pointed out, this support is had by the use of the intermediate block 200 which is a part of the form block and which is operated in such manner as to permit of the usual 85 operations of form blocks 28 and 50. It will thus be seen that the successful operation becomes more or less dependent upon the use of a three-member form block instead of a two-member block as in the usual shell 90 forming operations. Obviously, such three-member form could be employed in connection with the usual shell formation—intermediate block 200 remaining more or less inactive—so that with blocks of the proper 95 size, the composite form shown herein may be used for the production of either one or two-piece shell structures.

The several blocks—which are preferably of similar dimensions on a plane taken transversely of the block axis—are removably supported in order that the changes may be made to take care of conditions brought about by changes in the dimensions of the product, the adjustability in different parts 100 permitting the desired flexibility in operation to take care of these differences in sizes.

It is to be understood, of course, that while I have, for illustrative purposes, used the particular form of apparatus disclosed in said patent as providing the general operation of the present invention, such invention is not limited to use in connection with this particular form of apparatus nor to the particular container structure formations disclosed herein, it being obvious that the invention may be employed in connection with specific forms of apparatus of various types and adapted to produce container structures of various types.

While I have herein shown and described an embodiment of the invention for carrying out the purposes herein disclosed, it will be readily understood that changes or modifications therein may be found desirable or essential in meeting the exigencies of use, and I desire to be understood as reserving the right to make any and all such changes or modifications as may be found desirable or necessary, in so far as the same

may fall within the spirit and scope of the invention as expressed in the accompanying claims when broadly construed.

What I claim is:

- 5 1. In an organized machine for folding blanks into container structures having marginal laps and wherein the laps are infolded into contact with interior faces of the structure walls, folding instrumentalities operative to fold a blank into structure formation, said instrumentalities including means for temporarily supporting the inner faces of the free edges of the structure walls during inturning of the marginal laps.
- 10 2. In an organized machine for folding blanks into container structures having marginal laps and wherein the laps are infolded into contact with interior faces of the structure walls, folding instrumentalities operative to fold a blank into structure formation, said instrumentalities including means for temporarily supporting the inner faces of the free edges of the structure walls during inturning of the marginal laps, said means being movable from supporting position during lap infolding movements.
- 15 3. In an organized machine for folding blanks into container structures having marginal laps and wherein the laps are infolded into contact with interior faces of the structure walls, folding instrumentalities operative to fold a blank into structure formation, said instrumentalities including a multiple-member form including means for temporarily supporting the inner faces of the free edges of the structure walls during inturning of the marginal laps.
- 20 4. In an organized machine for folding blanks into container structures having marginal laps and wherein the laps are infolded into contact with interior faces of the structure walls, folding instrumentalities operative to fold a blank into structure formation, said instrumentalities including a multiple-member form having one of its members operative to locate a lap in contact with its wall, said form having means for temporarily supporting the inner faces of the free edges of the structure walls during inturning of the marginal laps.
- 25 5. In an organized machine for folding blanks into container structures having marginal laps and wherein the laps are infolded into contact with interior faces of the structure walls, folding instrumentalities operative to fold a blank into structure formation, said instrumentalities including a multiple-member form, one of said form members being operative to locate a lap in contact with its wall, another of said members being operative to form a temporary support for the inner face of the free edge of such wall during inturning of the lap.
- 30 6. In an organized machine for folding blanks into container structures having marginal laps and wherein the laps are infolded into contact with interior faces of the structure walls, folding instrumentalities operative to fold a blank into structure formation, said instrumentalities including a three-member form, the intermediate member being operative to form a temporary support for the inner face of the free edge of such wall during inturning of the lap.
- 35 7. In an organized machine for folding blanks into container structures having marginal laps and wherein the laps are infolded into contact with interior faces of the structure walls, folding instrumentalities operative to fold a blank into structure formation, said instrumentalities including a three-member form having its members in superposed relation, one of the outer members being operative to locate a lap in contact with its wall, the intermediate member being positionable to form a temporary support for the inner face of the free edge of such wall during inturning of the lap.
- 40 8. In an organized machine for folding blanks into container structures having marginal laps and wherein the laps are infolded into contact with interior faces of the structure walls, folding instrumentalities operative to fold a blank into structure formation, said instrumentalities including a three-member form having its members in superposed relation, two of said members forming a unit and being yieldably connected together to permit relative movement within predetermined limits, said form members being movable to locate said unit in spaced relation to the third member of the form during inturning of the lap and being shiftable toward a position of substantial contact relation during movements of the lap into contact with its wall.
- 45 9. In an organized machine for folding blanks into container structures having marginal laps and wherein the laps are infolded into contact with interior faces of the structure walls, folding instrumentalities operative to fold a blank into structure formation, said instrumentalities including a three-member form having its members in superposed relation, two of said members forming a unit and being yieldably connected together to permit relative movement within predetermined limits, said form members being movable to locate said unit in spaced relation to the third member of the form during inturning of the lap and being shiftable toward a position of substantial contact relation during movements of the lap into contact with its wall.
- 50 10. In an organized machine of the character described, a form comprising three superposed relatively-movable members.
- 55 11. In an organized machine of the character described, a form comprising three superposed members movable relatively to each other, two adjacent members being yieldably connected to permit relative movement therebetween within predetermined limits, said pair of members being movable bodily relative to the third member.
- 60 12. In an organized machine of the character described, a form comprising three su-

ginal laps and wherein the laps are infolded into contact with interior faces of the structure walls, folding instrumentalities operative to fold a blank into structure formation, said instrumentalities including a multiple-member form having a shiftable member operative to form a support for the inner faces of the free edges of the structure walls during inturning of the marginal laps.

7. In an organized machine for folding blanks into container structures having marginal laps and wherein the laps are infolded into contact with interior faces of the structure walls, folding instrumentalities operative to fold a blank into structure formation, said instrumentalities including a three-member form, the intermediate member being operative to form a temporary support for the inner face of the free edge of such wall during inturning of the lap.

8. In an organized machine for folding blanks into container structures having marginal laps and wherein the laps are infolded into contact with interior faces of the structure walls, folding instrumentalities operative to fold a blank into structure formation, said instrumentalities including a three-member form having its members in superposed relation, one of the outer members being operative to locate a lap in contact with its wall, the intermediate member being positionable to form a temporary support for the inner face of the free edge of such wall during inturning of the lap.

9. In an organized machine for folding blanks into container structures having marginal laps and wherein the laps are infolded into contact with interior faces of the structure walls, folding instrumentalities operative to fold a blank into structure formation, said instrumentalities including a three-member form having its members in superposed relation, two of said members forming a unit and being yieldably connected together to permit relative movement within predetermined limits, said form members being movable to locate said unit in spaced relation to the third member of the form during inturning of the lap and being shiftable toward a position of substantial contact relation during movements of the lap into contact with its wall.

10. In an organized machine of the character described, a form comprising three superposed relatively-movable members.

11. In an organized machine of the character described, a form comprising three superposed members movable relatively to each other, two adjacent members being yieldably connected to permit relative movement therebetween within predetermined limits, said pair of members being movable bodily relative to the third member.

12. In an organized machine of the character described, a form comprising three su-

- perposed members movable relatively to each other, the outer members of the form being independently operable to provide relative movements therebetween, the intermediate 5 member of the form being yieldably supported by one of said outer members and having its movements relative to such supporting member controlled by the third member.
- 10 13. In an organized machine of the character described, a form comprising three superposed members movable relatively to each other, the intermediate member being supported by and having a lost-motion operation with respect to one of the other members to permit relative movement therebetween, the remaining member being operative to control such relative movements.
14. In an organized machine for folding 20 blanks into container structures having marginal laps and wherein the laps are infolded into contact with interior faces of the structure walls, folding instrumentalities operative to fold a blank into structure formation, 25 said instrumentalities including devices for turning in the marginal laps, and means for temporarily clamping the opposing faces of the upper edges of the structure walls and operative when said devices begin the turn- 30 in movement of the lap, said means being rendered inactive in advance of infolding of the lap into contact with the wall.
15. In an organized machine for folding blanks into container structures having mar- 35 ginal laps and wherein the laps are infolded into contact with interior faces of the structure walls, folding instrumentalities operative to fold a blank into structure formation, said instrumentalities including devices op- 40 erative to turn in upstanding marginal laps, shiftable means for temporarily supporting the inner faces of the free edges of the structure walls during such lap inturning operation, means external of the structure walls 45 and adapted to coöperate with said supporting means to clamp said walls, said coöperating means being rendered active to clamp the walls in advance of device activity to turn the laps from upstanding position, and 50 means for infolding the turned-in laps when said supporting means has been shifted from its clamping position, said external means being operative to release the clamping action in advance of infolding operation.
- 55 16. In an organized machine for folding blanks into container structures having marginal laps and wherein the laps are infolded into contact with interior faces of the structure walls, folding instrumentalities opera- 60 tive to fold a blank into structure formation, said instrumentalities including devices operative to turn in upstanding marginal laps, shiftable means for temporarily sup- 65 porting the inner faces of the free edges of the structure walls during such lap inturn-
- ing operation, means external of the structure walls and adapted to coöperate with said supporting means to clamp said walls, said coöperating means being rendered active to clamp the walls in advance of device 70 activity to turn the laps from upstanding position, and means for infolding the turned-in laps when said supporting means has been shifted from its clamping position, said external means being operative to release the 75 clamping action in advance of infolding operation and operative to apply a setting pressure to the infolded laps when said infolding means has completed its infolding operation.
- 80 17. In an organized machine for folding blanks into container structures having marginal laps and wherein the laps are infolded into contact with interior faces of the structure walls, folding instrumentalities opera- 85 tive to fold a blank into structure formation, said instrumentalities including a multi-member form, devices for turning in upstanding marginal laps, external pressure-applying means, and means for correlating 90 the operations of the form, devices, and said pressure-applying means to provide the following cycle of operations: apply a clamping action to the structure walls at the free edges of said walls, inturn the laps from 95 the upstanding position, release the clamping action and expose the inner faces of the wall free edges, infold the inturned laps into contact with such exposed faces, and apply a setting pressure to the infolded laps.
- 100 18. In an organized machine for folding blanks into container structures having marginal laps and wherein the laps are infolded into contact with interior faces of the structure walls, folding instrumentalities opera- 105 tive to fold a blank into structure formation, said instrumentalities including a multi-member form, devices for turning in upstanding marginal laps, external pressure-applying means, and means for corre- 110 lating the operations of the form, devices, and said pressure-applying means to provide the following cycle of operations: apply a clamping action to the structure walls at the free edges of said walls, inturn the laps from 115 the upstanding position, release the clamping action and expose the inner faces of the wall free edges, infold the inturned laps into contact with such exposed faces, and apply a setting pressure to the infolded laps, said pressure-applying means being active both in the clamping and the setting pressure actions, the movements of said latter means being controlled to provide a light pressure during the clamping action and a heavy 120 pressure during the setting action.
- 125 19. In an organized machine for folding blanks into container structures having marginal laps and wherein the laps are infolded into contact with interior faces of the struc- 130

- ture walls, folding instrumentalities operative to fold a blank into structure formation, said instrumentalities including a multi-member form, devices for turning in upstanding marginal laps, external pressure-applying means, and means for correlating the operations of the form, devices, and said pressure-applying means to provide the following cycle of operations: apply a clamping action to the structure walls at the free edges of said walls, inturn the laps from the upstanding position, release the clamping action and expose the inner faces of the wall free edges, infold the inturned laps into contact with such exposed faces, and apply a setting pressure to the infolded laps, said pressure-applying means being active both in the clamping and the setting pressure actions, the movements of said latter means being controlled to provide a light pressure during the clamping action and a heavy pressure during the setting action, the structure walls being held stationary between the successive pressure applications.
20. In an organized machine for folding blanks into container structures and wherein multi-ply end formations are produced, folding instrumentalities operative to fold a blank into structure formation, said instrumentalities including a form, means co-operating with the form for folding the blank to place end-forming elements in up-

standing position, and means for folding said upstanding portions into a two-ply formation and inturning the folded structure relative to the form, opposing means at a container end being relatively operative to locate one two-ply formation in advance of the other during movements of both formations to the inturned position.

21. In an organized machine for folding blanks into container structures and wherein multi-ply end formations are produced, folding instrumentalities operative to fold a blank into structure formation, said instrumentalities including a form, means co-operating with the form for folding the blank to place end-forming elements in upstanding position, and means for folding said upstanding portions into a two-ply formation and inturning the folded structure relative to the form, said means including reciprocating frames each carrying a folding device operative in connection with the formation at one end of the container, each device including a pivoted folding element, and means co-operating with said elements for automatically providing a pivotal action thereof during the reciprocating movements of the frames.

In testimony whereof I have hereunto set my hand.

WILLIAM HENRY STREEPER.
